US00D754637S

(12) **United States Design Patent**
Harper

(10) **Patent No.:** **US D754,637 S**
(b5) **Date of Patent:** **** Apr. 26, 2016**

(54) **HEADSET ADAPTER AND AUDIO CONTROLLER**

(71) Applicant: **Plantronics, Inc.**, Santa Cruz, CA (US)

(72) Inventor: **Pierre Harper**, Santa Cruz, CA (US)

(73) Assignee: **Plantronics, Inc.**, Santa Cruz, CA (US)

(**) Term: **14 Years**

(21) Appl. No.: **29/512,747**

(22) Filed: **Dec. 22, 2014**

(51) **LOC (10) Cl.** **14-01**

(52) **U.S. Cl.**

USPC **D14/217; D14/206**

(58) **Field of Classification Search**

USPC D14/217, 206, 137, 240, 256, 265, 188, D14/192, 433, 372; 379/430, 422; 381/370,

381/371, 375; D29/112; 2/411, 421, 422

Primary Examiner — Paula Greene

(57) **CLAIM**

The ornamental design for a headset adapter and audio controller, as shown and described.

DESCRIPTION

FIG. 1 is a front perspective view of a headset adapter and audio controller showing my new design;

FIG. 2 is a back perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines showing the unclaimed features form no part of the claimed design.

1 Claim, 4 Drawing Sheets
